CLAIM

The ornamental design for an air compressor, as shown and described.

DESCRIPTION

FIG. 1 is a perspective view of an air compressor showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof with a battery; and,

FIG. 10 is another perspective view thereof with a battery. The evenly spaced dashed broken illustrate portions of the air compressor that form no part of the claimed design. The long dash-short dash bolded broken lines in FIGS. 2, 4 and 10 define the bounds of the claimed design and form no part thereof. The evenly spaced dashed broken lines showing a battery in FIGS. 9 and 10 are for the purpose of illustrating environmental structure, and form no part of the claimed design.
